UNITED STATES PATENT OFFICE

DONALD D. ANDERSON, OF CLACKAMAS, OREGON

AMUSEMENT DEVICE

Application filed April 23, 1928. Serial No. 272,340.

My invention relates to amusement devices in general, and particularly to such devices as are used in amusement parks, at street carnivals and like places. The object of my invention is to provide a combative device by means of which two or more persons may engage in hostilities through the manipulation of dummies or manikins operated by the persons themselves. Said manikins are preferably designed to imitate pugilists, and are so illustrated and described herein, although other forms of manikins could be used if desired. I accomplish the above object by means of the construction illustrated in the accompanying drawings, which are a part of this application for Letters Patent, like characters of reference indicating like parts throughout the several views thereof, and in which:

20 Fig. 1 is a perspective view of my device.

Fig. 2 is a partial transverse sectional elevation of the same, illustrating the manner of mounting the movable carriages which bear the manikins.

25 Fig. 3 is an enlarged scale view of one of the manikins and its operating mechanism as mounted upon one of the carriages.

Fig. 4 is a further enlarged view of the mechanism operating the arms of the manikin, hereinafter called the arm unit.

Fig. 5 is a plan view of one of the manikin arms.

Fig. 6 is a front elevation of one of the manikin legs.

35 Fig. 7 is a plan view of the subject matter of Fig. 6 in the direction of the arrow 7.

Fig. 8 is a section upon the line 8—8 of Fig. 6.

40 Fig. 9 is a fragmentary elevation of the rod joints in Fig. 4 in the direction of arrow 9.

Fig. 10 is a side elevation of the mechanism that operates the arm unit of Fig. 4, and also operates to advance and retreat the manikin, and to rotate the same, hereinafter called the operating unit.

Fig. 11 is a plan view of a portion of the mechanism of Fig. 10 in the direction of arrow 11.

50 Fig. 12 is a rear elevation of the mecha-

nism of Fig. 10 in the direction of arrow 12.

Fig. 13 is a front elevation of the mechanism of Fig. 10 in the direction of arrow 13.

Fig. 14 is a detail of one of the push rods as shown in Fig. 10. 55

Fig. 15 is a plan view of the turn table of the mechanism shown in Fig. 10.

Fig. 16 is a sectional view of the subject matter of Fig. 15 illustrating the clutch device that secures the manikin upon the turn table. 60

Fig. 17 is a section of the operating unit taken upon line 17—17 of Fig. 3.

Fig. 18 is a view of the trigger system that operates to release the manikin from the turntable, hereinafter called the trigger unit. 65

Fig. 19 is a front elevation of the manikin frame in the direction of arrow 19 in Fig. 18.

Fig. 20 is a section upon line 20—20 of Fig. 19. 70

Fig. 21 is a section upon line 21—21 of Fig. 19.

In general my device consists of a plurality of pugilistic manikins, each mounted upon a carriage that is slidable backward and forward upon a suitable structure, said carriages carrying each a turn table upon which is secured the respective manikin and also the operating unit, which consists of mechanism for operating the manikin in all the movements hereinafter described. The minimum 80 number of manikins is two, being a pair of opposed pugilists, but there may be a greater number if desired, preferably a plurality of pairs of opposed manikins, as shown in Fig. 1. 75

The structure upon which my device is 85 mounted is preferably made up of a platform upon which those persons operating the device may conveniently stand, as shown at 30 in Figs. 1 and 2. Rising from said platform are elevated sides 31 upon the upper 90 ends of which is mounted a pugilistic ring consisting of floor 32, posts 33, and ropes 34, all to simulate a prize ring. A housed carriage is provided for each of the manikins, which carriage may be moved towards or 95 away from the ring center at the desire of the operator, as hereinafter explained. To facilitate the movement of said carriages I provide each with wheels 35 rolling upon suitable tracks 36 as shown in Fig. 2, the 100

carriage sliding within openings 36 and 37 in the sides and the floor respectively. Operating handles 38 are provided upon the outer ends of each carriage conveniently for the operator to grasp for the purpose of operating the manikin as hereinafter described, and by pushing or pulling upon said handles in unison the operator may move the carriage inwardly or outwardly as desired without operating any part of the manikin. Thus each operator may cause his manikin to advance to battle or retreat as may be desired during the period of operation of the device.

Securely mounted upon each carriage is a longitudinally disposed member 39, upon the outer end of which member is mounted a rotatable shaft 40. A disc 41 is secured to the upper end of said shaft 40 to rotate therewith. Upon the opposite or inner end of the member 39 is mounted a second rotatable shaft 42, which carries upon the upper end thereof a turn-table 43, upon which turn-table the manikin is mounted as hereinafter described. Trunnions 44 are pivoted upon the hub of disc 41 as shown in detail in Fig. 12, so that said trunnions may oscillate in vertical planes, and upon each of said trunnions is oscillatably mounted an operating handle 38. Said handles project upward through orifices in the disc 41, which orifices are sufficiently large to afford the handle therein movement in every direction. Thus the handles may be moved forward and backward upon the trunnions as shown in Fig. 10, or they may be moved sidewise upon the pivotal point of the trunnion as shown in Fig. 12. The movement of each handle is therefore universal. Besides moving said handles as thus described they may be simultaneously pushed or pulled away from or towards the operator, and thus the carriage may be moved towards or away from the ring center to advance or retreat the fighting manikin as the operator desires. Furthermore if one of the handles is pulled towards the operator while the other is pushed away from the operator a couple is established which will operate to rotate the disc 41 upon the shaft 40. By the establishment of such a couple I provide that the turn-table 43 shall be rotated. To accomplish this I provide upon the lower end of the shaft 40 a cross piece 45 transversely positioned relatively to the member 39. Upon the lower end of the shaft 42 I secure a sprocket 46 having thereon a chain 47, the ends of said chain being connected by rods 48 to the said cross piece 45, whereby when the disc 41 is rotated the turn-table 43 is likewise rotated, and thus the operator may at will rotate the manikin which is mounted upon the turn-table.

From the above description it is obvious that with suitable pressure upon the handles 38, which pressure is not of the sort to rotate said handles upon the trunnions 44, the car-

riage may be slidably moved forward and backward and the manikin turned to the right or the left, either simultaneously or independently, as the operator desires.

The arm unit of the manikin is equipped with two movements, the arm raising movement and the arm flexing movement, and to effect said movements of the manikin arms from the operator's position I provide the following mechanism for the operating unit. There being two arms and two movements for each I provide four tappets 50 vertically and slidably mounted upon the turn-table 43, said tappets having cupped upper ends, the concave side of said cupped ends being positioned upward, as shown in detail in Fig. 10. These tappets are symmetrically arranged upon said turn-table, the two forward tappets operating the arm raising mechanism of the manikin, and the two rearward tappets operating the arm flexing mechanism thereof. To operate the arm raising tappets I provide levers 51 pivoted beneath the turn-table, and having slots to receive the turned ends of the tappets, as shown in Fig. 10. Pivotally connected to the disc 41 are rods 52 which slide longitudinally within suitable supports 53 upon the member 39. Upon said rods are pivoted arms 54 depending therefrom, and the lower ends of said arms are connected with the respective lever 51 in any convenient manner that will operate said lever 51 from its respective arm 54. A convenient method of accomplishing said connection is by means of a flexible member 55 mounted upon sheaves 56, which sheaves are mounted below the shaft 42 and substantially in alignment therewith, as shown in detail in Figs. 10 and 13. A bell crank 57 is mounted beneath the disc 41 as shown in Figs. 10 and 12, the horizontal end thereof being slotted to receive one of the trunnions 44 and the vertical end thereof being connected to the arm 54 by a link 58. Thus when the respective handle 38 is moved sidewise as shown in Fig. 12 the bell crank is oscillated upon its pivotal point, thus operating the arm 54 and through the flexible member the lever 51 and the tappet 50 respective thereto. Thus by moving the handle 38 sidewise the operator may cause the arm raising mechanism of the manikin to raise or lower the arms thereof, causing them to assume such positions as are illustrated in Fig. 4, and all positions therebetween.

To operate the arm flexing tappets I provide a lever for each, said levers 60 being pivotally mounted beneath the turn-table 43 and being slotted to receive the turned end of the respective tappet, as shown in detail in Figs. 10 and 14. Arms 61 are pivoted upon the rods 52 and connected with suitable swivel links 62 to the lower end of the respective handle 38. The lower end of the arm 61 is connected in any suitable manner with the

lever 60 to operate the latter, a convenient manner of accomplishing this being by means of a flexible member 63 passing over sheaves 64, which sheaves are mounted beneath the 5 shaft 42 and substantially alined therewith, and sheave 65 mounted beneath the turn-table 43. Thus when the respective handle 38 is moved backward and forward its corresponding tappet 50 is moved downward and upward 10 respectively. By thus moving the handles 38 forward and backward the operator may cause the arm flexing mechanism of the manikin to flex the arms thereof into such positions as are illustrated in Fig. 4, and all 15 positions therebetween.

By thus moving the handles 38 sidewise and forward and backward all combinations of arm raising and arm flexing movements may be attained, and the manikin may be 20 caused to strike blows simulating most blows used by pugilists, such as upper-cuts, straight arm jolts, and the like.

Each manikin is provided with four push-rods, two of which operate the arm raising 25 mechanism and are positioned to enter the cupped ends of the tappets 50 respective thereto when the manikin is mounted in position upon the turn-table 43. Said arm raising push rods are designated by 70 in Figs. 30 3 and 4. A frame is provided for the manikin which consists of a rod member 71 secured upon the turn-table 43 by a clutch mechanism hereinafter to be described. Said rod member 71 terminates at its upper end in 35 a head upon which is pivoted a torso frame 72, by means of a shaft 73. Said frame is designed to give suitable support to the various shafts required to mount the operating levers and arms as hereinafter described, and 40 the frame may be of any suitable shape for such purpose. Each arm of the manikin is pivoted upon said frame by a shaft 74 at a point that corresponds to the shoulder of the manikin. Immediately beneath said shafts 45 74 are shafts 75, and upon the outer ends thereof are secured arms 76. One of the upper arm members 77 is secured upon the outer end of said shaft 74. Said upper arm member may be of any convenient construc- 50 tion, that shown in the drawings being a pair of members 77 rigidly connected by a suitable cross piece 78, as illustrated in Fig. 5. The fore arm member 79 is pivoted to the members 77 at 80, and may conveniently be 55 formed in the shape of a hair-pin with an enlarged outer end as shown in Fig. 5, said enlarged end forming the fist of the manikin. A pair of links 81 and 82 are pivotally connected at their middle ends, as at 83 and 60 the outer end of link 82 is pivoted to the fore-arm member 79 near the outer end thereof, as at 84. The outer end of the link 81 is pivoted to the arm 76, as shown in Figs. 3 and 4. A lever member 85 is rigidly secured upon 65 the link 82 of the forearm, and said member

85 is pivotally mounted upon the pivot 80 of the arm members. The push rod 70 is pivotally connected at 90 to a pushrod 91, which latter pushrod is pivotally attached to an 70 arm 92 secured upon the shaft 75. Thus when said push rod 70 is moved up and down by the operation of its respective tappet 50 its re- 75 spective manikin arm is raised or lowered.

To operate the arm flexing mechanism I provide for each arm a push rod 93 which coacts with its respective one of the tappets 50 to receive vertical motion therefrom. Said push rod 93 is pivotally connected to a push rod 94, said pivotal joint being shown at 95, and being similar to that shown in detail in Fig. 9. The push rod 94 is pivotally connected to an arm 96 secured upon shaft 75. Thus vertical reciprocation of the push rod 94 rotates the shaft 75 and thereby through means of the member 81 rotates the member 82 about the pivotal point 80 in the arm. This in turn rotates the forearm member 79 about the same pivotal point 80, thus causing the flexing of the arm about the pivotal point 80 which is the elbow joint of the manikin. Thus 90 the arm may be flexed at the elbow into any position shown in dotted lines in Fig. 4, and any intermediate positions.

By means of the arm moving mechanism described above, combined with the rotation of the manikin and the moving of the same backward and forward, it is obvious that many blows such as straight arm thrusts, upper cuts and side swipes, used by pugilists, may be closely simulated by operation of the 95 manikin from the handles 38.

In order to render the game decisive there must be vulnerable points upon each manikin which points upon being struck by an opposing manikin will cause the manikin so struck to fall. I provide preferably three such vulnerable points, one in the chin, one in the chest and one in the back of the manikin, at each point there being a suitable trigger to receive the blow and thus to set in action suitable release mechanism.

Located at the chin of the manikin is a trigger 100 having integral therewith an arm 101 which is secured upon a shaft 102 journaled in the frame 72, as shown in Figs. 3, 115 18 and 19. Also secured upon said shaft 102 is an arm 103. A lever 104 is pivoted to an extension 105 of the frame 72, and said lever is connected to the arm 103 by a rod 106. A spring 107 serves to retain said lever and thereby said trigger in its initial position, ready to receive a blow thereupon. The lower end of lever 104 is crescent shaped as shown at 104', and engages a rod 105' to retain said rod in its uppermost position within its guide 106'. Said rod 105' is pivotally connected to a latch member 108 which latch member is pivotally mounted upon the frame 72 by means of the shaft 109; lugs 110 upon the head of the member 71 whereupon the 120 125 130

torso frame 72 is pivoted are provided to engage said latch member 108 and thereby retain said torso frame 72 in upright or vertical position.

5 Upon the lower end of member 71 is secured a flange 111 having a lug 112 thereupon adapted to engage a suitable depression in the turn-table 43 for the purpose of centering the manikin upon said table. To secure the 10 manikin in place upon the turn-table I provide a suitable clutch device, a convenient form thereof being a pair of levers 113 pivoted upon lugs 114 which lugs are integral with said flange 111. Slidably mounted in 15 guide 106' is a push rod 115 terminating at its upper end in an arm 116, which arm crosses the crescent shaped portion of lever 104 immediately adjacent thereto. A pin 117 is provided upon said arm 116 adapted to be 20 engaged by the crescent shaped portion of the lever 104 and depressed thereby, thus depressing the push rod 115. Said push rod is connected by a link to the ends of the clutch 25 levers 113. Said link consists of a tubular portion 118 wherein is telescoped a rod 119, the distance of entrance of said rod into said tube being determined by a collar 120 secured upon said rod. The tubular member 118 is pivoted to the lower end of the 30 push rod 115, and the rod 119 is likewise pivoted to the clutch levers 113.

The lower ends of the clutch levers 113 project downward through orifices 121 in the turn-table 43 and are provided with hooked 35 ends 122 to engage the lower surface of said turn-table and thus secure the manikin in place thereupon.

When a blow is received upon the trigger 40 100 it is obvious that latch member 108 is immediately released from its engaging lugs 110, and then the upper torso frame 72 is free to rotate about the shaft 73, as shown in dotted lines in Fig. 18. Substantially simultaneously with the releasing of the torso 45 frame 72 as just described the clutch levers 113 are released from engagement with the turn-table 43 by means of the mechanism just described. Thus the manikin is freed from its position upon the turn-table, and 50 falls prone upon the platform 32 of the ring structure.

A trigger 130, located at the back of the manikin, is attached to the lever 104, and if the manikin is turned so that an opposing 55 manikin strikes said trigger 130 the mechanism just described will be operated and the manikin released from the turn-table, falling substantially as if struck upon the chin trigger 100.

60 A body trigger 131 is also provided, having an arm 132 pivoted upon the frame 72 by means of shaft 133. A link 134 connects one end of said arm with the upper end of the arm 116. Thus when the trigger 131 is 65 struck the arm 116 and the push rod 115 are

moved downward to release the clutch levers 113 and set the manikin free from the turn-table 43. Since a pugilist struck upon the body usually falls backward without bending at the hip I have provided that the 70 trigger operates independently of the latch member 108, since said trigger 131 is not in any manner connected with said latch member. Therefore when the trigger 131 is struck the manikin is released to fall backwards, 75 but is still retained unbending about the shaft 73.

To add interest and attraction to my device, and to simulate the action of a pugilist quite closely, I provide the manikins with movable 80 legs, the same actuated from the movable arms, and caused to take positions as shown in Fig. 1 during action.

For this purpose I pivot a thigh member 140 upon the shaft or hip joint pivot 73 by 85 means of a hanger 141. This thigh member is positioned transversely of the manikin frame, and pivotally attached thereto at the ends thereof are two depending leg members 142 and 143. The lower ends of said members 142 and 143 are joined by a link 144. Lower leg members 145 and 146 are pivoted upon the lower ends of the members 142 and 143, and upon the lower ends of said lower leg members 145 and 146 is pivoted a transversely 90 disposed foot member 147. An arm 148 is rigidly secured upon the shaft 73, and another arm 149 is secured upon the leg member 143. These two arms are pivotally connected by a 95 rod 150, as shown in Figs. 3 and 4. A third 100 arm 151 is secured to the lower leg member 145, and the arms 149 and 151 are also pivotally connected by a rod 152. Adjacent the leg thigh member 140, and above the same, an arm 153 is secured upon a shaft 154, and upon 105 said shaft is secured a second arm 155. The outer end of said second arm 155 is slotted to receive the pivot pin of the pivotal joint between the push rods 70 and 91, as shown in detail in Fig. 9. The outer end of the arm 153 110 is pivotally connected with the thigh member 140 at the pivotal point of said thigh member and the leg member 142, by a rod 156. When the push rod 70 is operated to move the manikin arm the arms 155 and 153 will be rotated, 115 and through the rod 156 the leg thigh member 140 will be rotated about the hip joint shaft 73. By reason of the leg members 143 and 145 being pivotally joined by the rod 152 and likewise to the stationary arm 148, said leg 120 members will assume various positions as they are moved by the leg thigh member 140. These various positions follow the positions of the manikin arms, as is obvious from Fig. 4, and thus the attitude of a pugilist both as 125 regards the arms and the legs is simulated.

My invention lies primarily in the combination of a pugilistic ring structure with provision at its base for operators to stand, a plurality of pugilistic manikins movably mount- 130

ed within the ring, and mechanism operated by a person respective to each manikin, said mechanism causing the manikin to make various movements simulating those of a pugilist; 5 and secondarily in certain features of said mechanism that are indispensable to the operation of the manikin.

It is to be understood that the mechanism above described is to be clothed in suitable 10 clothing, and heads and boxing gloves are to be provided, the same to be secured to the frame of the manikin in any suitable and convenient manner. The manner of construction and securing said clothing and other 15 parts of the manikin is no part of the present invention, and therefore is not described or claimed herein. Fig. 3 shows in light line outlines such a figure of a pugilist encasing the mechanism of the manikin, and Fig. 1 20 shows the appearance of such manikins in the ring.

My invention may be made of any size, and constructed of any materials deemed convenient and suitable for a device of this character, 25 and while I have illustrated and described a form of construction and arrangement of parts found desirable in materializing my invention, I wish to include in this application for Letters Patent all mechanical equivalents 30 and substitutes that may fairly be considered to come within the scope and purview of my invention as defined in the appended claims.

Having disclosed my invention so that others may be enabled to construct and to use 35 the same, what I claim as new and wish to secure by Letters Patent is:

1. In an amusement device: a platform constituting a pugilistic ring; operators' stations adjacent said platform; oppositely disposed 40 carriages slidably mounted within said ring; turntables upon said carriages; pugilistic manikins mounted upon certain of said turntables, and having movable arms; operating handles upon other of said turntables adjacent 45 said operators' stations; mechanism connecting said handles with their respective manikin to operate the latter and mechanism whereby rotation of the turntable respective to said handles will rotate the turntable 50 respective to the corresponding manikin.

2. In an amusement device: a pugilistic inclosure; operators' stations adjacent said inclosure; a turntable within said inclosure; a turntable at said operators' stations; pugilistic manikin mounted upon said former turntable; operating handles upon the turntable adjacent said operators' stations; and means operated by said handles to rotate the turntable upon which said manikin is mounted. 55

60 3. In an amusement device: a pugilistic inclosure; operators' stations adjacent said inclosure; pugilistic manikins mounted within said inclosure; arms upon said manikins having pivotal elbow joints; operating handles adjacent said operators' stations; and

mechanism connecting each of said handles with a respective manikin arm for the purpose of flexing said arm at the pivotal elbow joint thereof as said handle is operated, said mechanism consisting of an arm member, a lever arm pivoted to said arm member, a second lever arm adapted to operate said former lever arm, a vertically movable rod connected to said second lever arm, a tappet contacting with said rod, and means 70 to operate said tappet from one of said handles. 75

4. In an amusement device: a pugilistic inclosure; operators' stations adjacent said inclosure; pugilistic manikins mounted within said inclosure; arms pivotally mounted at the shoulders of said manikins; pivotal elbow joints in said arms; operating handles adjacent said operators' stations; mechanism connecting each of said handles with a respective manikin arm for the purpose of moving the arm about its pivotal shoulder joint as the handle is operated; and mechanism independent of said former mechanism connecting each of said handles with a respective manikin arm for the purpose of flexing said arm at the pivotal elbow joint thereof as said handle is operated. 80 85 90

5. In an amusement device: a pugilistic inclosure; operators' stations adjacent said inclosure; pugilistic manikins having movable arms adapted to strike blows, mounted within said inclosure; means for operating said arms from said operators' stations; a clutch holding said manikin in upright position and forming the only connection between said manikin and said inclosure; and a trigger upon said manikin connected to said clutch by clutch releasing mechanism operable when said trigger receives a blow thereupon to totally release said manikin from connection with said inclosure. 95 100 105

6. In an amusement device: a pugilistic inclosure; operators' stations adjacent said inclosure; pugilistic manikins having movable arms adapted to strike blows, mounted within said inclosure; means for operating said arms from said operators' stations; a clutch device holding said manikin in upright position; a pivotal connection between the upper and the lower portions of said manikin at the hip joint thereof; latch mechanism at said pivotal connection adapted to hold the upper and lower portions of said manikin in alinement; a trigger upon said manikin; clutch releasing mechanism connecting said trigger with said clutch; and latch releasing mechanism connecting said trigger with said latch mechanism. 110 115 120

7. In an amusement device: a pugilistic inclosure; operators' stations adjacent said inclosure; oppositely disposed carriages slidably mounted within said inclosure; horizontally rotatable mechanism upon said carriages adjacent said operators' stations; turn- 125 130

tables upon said carriages; means to operate said turn-tables from said horizontally rotatable mechanism; and pugilistic manikins mounted upon said turntables.

5 8. In an amusement device: a pugilistic inclosure; a plurality of pugilistic manikins movably mounted within said inclosure, each of said manikins having a corresponding manikin upon the right and the left thereof; 10 manually operated mechanism for advancing and retreating each manikin; and manually operated mechanism for rotating each manikin to cause the same to face a corresponding manikin upon either side thereof; 15 said mechanism including operating handles located outside said inclosure.

9. In an amusement device: a manikin; arms upon said manikin; pivotal elbow joints upon said arms; vertically movable rods upon 20 said manikin; mechanism connecting each of said rods with the manikin forearm respective thereto; a control station remote from said manikin; and mechanism connecting said control station with said rods for 25 the purpose of flexing said arms at said pivotal joint.

10. In an amusement device: a manikin; a floor; clutch mechanism to secure said manikin in an upright position upon said floor; 30 clutch releasing mechanism to totally release said manikin from said floor and means to operate said releasing mechanism from an operating station remote from said manikin.

35 In witness whereof I claim the foregoing as my own I hereunto affix my signature at Portland, county of Multnomah, State of Oregon, this 17th day of April 1928.

DONALD D. ANDERSON.
